H. E. DUNHAM

ELECTRON DISCHARGE APPARATUS

Filed March 23, 1921

FIG. 1.

FIG. 2.

Inventor:
Harry E. Dunham,
by *Albert S. Davis*
His Attorney.

Patented Sept. 25, 1923.

1,469,075

UNITED STATES PATENT OFFICE.

HARRY E. DUNHAM, OF SCHENECTADY, NEW YORK, ASSIGNOR TO GENERAL ELECTRIC COMPANY, A CORPORATION OF NEW YORK:

ELECTRON-DISCHARGE APPARATUS.

Application filed March 23, 1921. Serial No. 454,829.

To all whom it may concern:

Be it known that I, HARRY E. DUNHAM, a citizen of the United States, residing at Schenectady, county of Schenectady, State of New York, have invented certain new and useful Improvements in Electron-Discharge Apparatus, of which the following is a specification.

My present invention relates to electron discharge apparatus and more particularly to that type of apparatus the operation of which depends upon producing and varying the emission of secondary electrons from a cold electrode.

One of the objects of my invention is to provide a simple and efficient means and method for operating a device of the type mentioned.

A more specific object of my invention is to provide a simple and efficient apparatus and method for receiving continuous wave signals whereby an audible indication of desired signals which are normally incapable of giving such an indication may be obtained. In attaining the more specific object of my invention I include in the circuit upon which signaling currents to be detected are impressed, an electron discharge device so that the signaling current flowing in the circuit is carried through this device by means of electrons. By varying the number of electrons which can flow between the electrodes of this device the resistance of the circuit may be varied in any manner desired. In the present case I prefer to vary the number of electrons flowing by means of an electrostatic field produced upon a grid electrode which is properly positioned to vary the flow of electrons. If the potential of this grid electrode is varied periodically between certain positive and negative values at a frequency somewhat different from that of the signaling currents to be detected, the resistance of the signaling circuit will be varied periodically between maximum and minimum values and the current in the circuit may be caused to vary at an audible frequency. I also preferably arrange the electron discharge device in such a way as to produce a negative resistance between the cathode and the controlling grid. By tuning the circuit between the cathode and controlling grid oscillations will be produced in that circuit and the potential of the grid will automatically be caused to vary

periodically at the frequency of the oscillations produced.

The specific form of electron discharge device which I prefer to employ comprises an electron emitting cathode, an anode, a third electrode and a discharge controlling grid. A constant positive potential is impressed upon the anode and a smaller positive potential is impressed upon the third electrode. If these potentials are properly chosen secondary electrons will be emitted from the third electrode which will be attracted by the anode. It has been customary in the past to operate devices of the type described in such a way that a negative resistance is produced between the cathode and the third electrode. If under this condition of operation signals are impressed upon the circuit between the cathode and third electrode by means of the usual tuned receiving circuit, the circuit has a tendency to oscillate continuously at the signaling frequency. To overcome this tendency special means must be provided which tend to complicate the operation of the system.

In detector systems of the class to which my invention belongs, it is desirable that a circuit be employed in which the current can flow in either direction. An inspection of the usual characteristic curve of the device described shows that there are two points where this last condition may be fulfilled, the first point being where the resistance of the circuit is negative and the potential of the third electrode is appreciably lower than that of the anode, and the second point occurring where the potential of the third electrode approaches that of the anode, and an increase in the potential of the third electrode is accompanied by a decrease in the number of secondary electrons which will be emitted and which will reach the anode. I have found that this second point on the characteristic curve is an especially suitable point to use for carrying out my invention and since the circuit has a positive resistance characteristic when operated with the potential of the third electrode chosen to fall at this point on the characteristic curve there is no tendency for the circuit to oscillate.

The novel features which I believe to be characteristic of my invention are set forth with particularity in the appended claims. My invention itself, however, both as to

its organization and method of operation will best be understood by reference to the following description taken in connection with the accompanying drawing in which Fig. 1 shows diagrammatically the preferred form of circuit arrangement for carrying my invention into effect, and Fig. 2 represents a set of characteristic curves showing the relation between current in the signaling circuit and the potential impressed upon that circuit for different values of potential of the controlling grid.

As indicated in Fig. 1 of the drawing, I utilize an electron discharge device 1 which comprises an electron emitting cathode 2, an anode 3, a third electrode 4 and a discharge controlling grid 5. The battery 6 which is connected in circuit between cathode and anode furnishes the operating potential for the anode. The second battery 7, which is connected in the circuit between cathode and third electrode furnishes the normal operating potential for the third electrode. A third battery 8 connected in the circuit between cathode and discharge controlling grid furnishes the normal operating potential for the grid. These potentials are so chosen that the circuit between cathode and discharge controlling grid will have a negative resistance by reason of the emission of secondary electrons from the grid 5, which flow to the anode 3. The potential of the battery 7 is also so chosen that secondary electrons will be emitted from the third electrode 4, which will flow to the anode 3, but in this case the potential is chosen to fall on or close to the point A on the characteristic curves of Fig. 2 instead of the point B, as has been customary in previous circuit arrangements in which devices of the type described have been employed. Signaling potentials received upon the antenna 9 are impressed upon the secondary of the transformer 10, which is included in the external circuit between cathode and third electrode. This circuit may be tuned to the signaling frequency by means of the usual variable condenser 11. Inductance 12 and capacity 13 are included in the circuit between cathode and grid 5 for tuning this circuit to a frequency slightly different from that of the signaling frequency. Inasmuch as this circuit has a negative resistance characteristic oscillations will be produced therein and the potential of the grid 5 consequently will be varied at a frequency corresponding to the frequency of the oscillations produced.

The operation of the device will best be understood by reference to the curves of Fig. 2 which show the relation between plate potential and plate current for different values of potential of the grid 5. The curve C represents the current for a high positive potential of the grid 5 and the curve E for a low or negative potential of the grid 5. It will

be apparent from an inspection of these curves that the effect of varying the grid potential is to produce a variation in the apparent resistance of the circuit between cathode and third electrode. In the normal operation of the system, the potential of the battery 7 being chosen to correspond to the voltage A at which the current flowing between cathode and third electrode is zero, as long as the potential remains at this point the variation in the potential of the grid 5 will produce no changes in the current flowing into the circuit between cathode and third electrode. If, however, a signaling potential is impressed upon the secondary of transformer 10 so that the total potential of the electrode 4 corresponds for example to the voltage F, a variation in the potential of the grid will vary the apparent resistance of this circuit between cathode and third electrode between a substantially infinite value at which the current is zero, and a much lower value at which the current is represented by the value G on the characteristic curve C. If the oscillations produced in the circuit of the grid 5 were of the same frequency as the signaling current and properly phased with respect thereto, signaling potentials of one sign would produce current between cathode and third electrode while signaling potentials of the opposite sign would produce no current in that circuit. The device then would in effect operate as a half wave rectifier to produce a unidirectional current between cathode and third electrode. If on the other hand currents produced in the grid circuit were of slightly different frequency from the signaling current, the current produced in the circuit between cathode 2 and third electrode 4 would consist of a number of current impulses in one direction followed by a number of current impulses in the opposite direction as the phase relations changed and a current would be produced in the telephone receiver 14 having an audible frequency component capable of affecting the telephone receiver. The current in this case would be of the same nature as that described in Goldschmidt Patent 1,087,113, and illustrated in Fig. 3^c of that patent.

While I have described the preferred embodiment of my invention, it will be apparent that my invention is by no means limited to the particular circuit arrangement or apparatus indicated, but that many modifications therein may be made without departing from the scope of my invention as set forth in the appended claims.

What I claim as new and desire to secure by Letters Patent of the United States, is—

1. Means for detecting high frequency signaling currents comprising an electron discharge device having an electron emitting cathode, an anode, and a third electrode, means for impressing a constant positive po-

tential upon the anode and means for impressing a smaller positive potential upon the third electrode, the potentials of said electrodes being so chosen that secondary electrons will be given off from the third electrode and the normal operating potential of the third electrode being of such a value that an increase thereof will cause a decrease in the number of secondary electrons which 10 will be given off from the third electrode.

2. Means for detecting high frequency signaling currents comprising an electron discharge device having an electron emitting cathode, an anode and a third electrode, 15 means for impressing a constant positive potential upon the anode, means for impressing a smaller positive potential upon the third electrode, the potentials of said electrodes being so chosen that secondary electrons will be given off from the third electrode and the potential of the third electrode being of such a value that an increase thereof will cause a decrease in the number of secondary electrons which will be given off 20 from the third electrode, and means for varying the potential of the third electrode in accordance with the signals to be detected.

3. The combination in a signal receiving system of an electron discharge device having an electron emitting cathode, an anode, 30 a third electrode and a discharge controlling member, means for producing an emission of secondary electrons from the third electrode, the potential of said third electrode being of such a value that an increase thereof will produce a decrease in the number of secondary electrons which will be given off, means for varying the potential of the third electrode in accordance with the signals to be 35 received, and means for varying the potential of the discharge controlling member at a frequency which is independent of the frequency of the signals.

4. The combination in a signal receiving system of an electron discharge device having an electron emitting cathode, an anode, a third electrode and a discharge controlling member, means for producing an emission of secondary electrons from the third electrode, 45 the potential of said third electrode being of such a value that an increase thereof will produce a decrease in the number of secondary electrons which will be given off, means for varying the potential of the third electrode in accordance with the signals to be received, means for producing an emission of secondary electrons from the discharge controlling member sufficient to produce a 50 negative resistance characteristic between cathode and discharge controlling member, producing oscillations by means of said device and applying the oscillations thus produced to the discharge controlling member.

5. The method of operating an electron

discharge device comprising an electron emitting cathode, an anode and a third electrode, which consists in applying a constant positive potential to the anode, applying to the third electrode a positive potential of such a value as to cause secondary electrons to be given off from the third electrode and that the number of secondary electrons given off will decrease if the potential of the third electrode is increased, and varying the potential of the third electrode in accordance with signals.

6. The method of operating an electron discharge device comprising an electron emitting cathode, an anode, a third electrode and a discharge controlling member to detect high frequency signals which consists in applying a constant positive potential to the anode, applying to the third electrode a positive potential of such a value as to cause secondary electrons to be given off from the third electrode, and that the number of secondary electrons given off will decrease if the potential of the third electrode is increased, varying the potential of the third electrode in accordance with the signals to be detected, and varying the potential of the discharge controlling member at a frequency which is independent of the signaling frequency.

7. The method of operating an electron discharge device comprising an electron emitting cathode, an anode, a third electrode and a discharge controlling member to detect high frequency signals which consists in applying a constant positive potential to the anode, applying to the third electrode a positive potential of such a value as to cause secondary electrons to be given off from the third electrode, and that the number of secondary electrons given off will decrease if the potential of the third electrode is increased, varying the potential of the third electrode in accordance with the signals to be detected, producing an emission of secondary electrons from the discharge controlling member sufficient to give the device a negative resistance characteristic between cathode and discharge controlling member, producing oscillations by means of said device and applying the oscillations thus produced to the discharge controlling member.

8. The method of operating an electron discharge device comprising an electron emitting cathode, an anode, a third electrode and a discharge controlling member to detect high frequency signals which consists in applying a constant positive potential to the anode, applying to the third electrode a positive potential of such a value as to cause secondary electrons to be given off from the third electrode and that the number of secondary electrons given off will decrease if the potential of the third electrode

is increased, varying the potential of the third electrode in accordance with the signals to be detected, producing an emission of secondary electrons from the discharge controlling member sufficient to give the device a negative resistance characteristic between cathode and discharge controlling member and periodically varying the potential of the discharge controlling member at a frequency slightly different from that of the signals to be detected.

In witness whereof, I have hereunto set my hand this 22nd day of March, 1921.

HARRY E. DUNHAM.
